UNITED STATES PATENT OFFICE.

JOHN A. MOORE AND JAMES W. BROWN, OF WOODVILLE, TENNESSEE.

FIRE-ESCAPE.

SPECIFICATION forming part of Letters Patent No. 240,162, dated April 12, 1881.

Application filed February 12, 1881. (No model.)

To all whom it may concern:

Be it known that we, JOHN A. MOORE and JAMES W. BROWN, of Woodville, in the county of Haywood and State of Tennessee, have invented a new and Improved Fire-Escape, of which the following is a specification.

The object of this invention is to provide a fire-escape which can be converted into a door-shutter, window-blind, or ladder at will; and it consists of a hinged frame from which the lazy-tongs are suspended, and within which they may be closed up by suitable devices to form a blind or shutter, said fire-escape frame being hinged to a door or window frame so as to swing outward and inward, after the manner of an ordinary blind or shutter; and it consists, further, of novel devices for adjusting the escape from any floor of the building to which it is applied.

Figure 1 represents an elevation of the fire-escape fully extended and swung at right angles to a building. Fig. 2 is an elevation of the outer face of the fire-escape closed, and serving as a blind or shutter. Fig. 3 is an elevation of the inner face of the fire-escape closed, and serving as a blind or shutter. Fig. 4 is a sectional plan on line *xx*, Fig. 2, of the fire-escape swung and held at right angles to a building. Fig. 5 is a cross-section on line *yy*, Fig. 3. Fig. 6 is a longitudinal elevation of a screw eye or ring for securing the device when closed.

Similar letters of reference indicate corresponding parts.

In the drawings, A represents the fire-escape, consisting of lazy-tongs A', whose sections are secured together where they cross each other by screw-eyes *a*, that serve as guides for the operating cord or rope E, and of horizontal cross-bars A², provided with slots *b* in their ends, that are secured across the lazy-tongs A' by bolts or screws *c*, that pass through the slots *b* into the ends of the lazy-tongs sections and form the pivots therefor. Said cross-bars A² serve as steps for ascending and descending the fire-escape, and the length of their slots *b* determines the distance between the steps.

B is a stout frame constructed with a horizontal top, *d*, and two depending parallel legs, *d'*, and to the top *d* of this frame B the top of the fire-escape A is centrally secured by an

eyebolt or screw-eye, *a'*, or other suitable device, so that said fire-escape A can be hoisted or closed up against said frame B, and thereby form a shutter or blind, as shown in Figs. 2 and 3. One leg, *d'*, of the frame B is entered down through eyebolts or hinges *f*, that are driven into or hinged upon the side of the building C, so that said frame B may swing horizontally.

Pivoted on the under side of the top of the window or door frame C' so as to move in a horizontal plane, is an elbow-lever, D, to the inner end of which is attached a cord or rope, D', that passes over suitable pulleys *g*, and is extended down through the different floors C² of the building C, so as to be within convenient reach of the occupants of said floors C². The other arm of said lever D presses against the inner face of the fire-escape A, so that by pulling down on said rope or cord D' the lever D is made to throw the frame B, with its contained fire-escape A, open on the hinges *f*, as shown in Figs. 1 and 4, and when thus thrown open the eyebolt or screw-eye *a'* will automatically engage in a suitable catch, *h*, that is secured on the side of the building C, and the frame and fire-escape B A be thus held at any desired angle to the building C, for the convenience of those wishing to descend or ascend by said escape. The portion A is raised and lowered by means of a cord or rope, E, that is made fast at one end about the screw-eye *a'* and passed down through all the screw-eyes *a* around a pulley, *i*, that is centrally secured on the lower cross-bar, A², then up through the screw-eyes *a a'* and into the building C, over suitable pulleys *k*, and down through the floors C², within convenient reach of the occupants thereof, and is secured at any convenient point.

On letting go the rope E, when the frame B is in the position shown in Figs. 1 and 4, the fire-escape A is extended to the ground, and can have its lower end secured by the engagement of its bottom hooks, *m*, in rings *n*, that are fixed in the pavement, or in any other convenient manner. These hooks *m* on the lower cross-bar, *a'*, of the device also serve to secure anything to that it may be desired to lower from a building—as, for instance, an infant in its crib, child in a basket, or an invalid not able otherwise to escape, or any

valuable article of furniture. The rapidity of descent will be regulated and controlled by means of the rope E, and by the same means the device will be elevated and closed upward 5 to form a door or shutter, as shown in Figs. 2 and 3. When raised and closed upward the screw eyes or rings o, that are substituted for bolts or screws c at a point about one-fourth of the way up from the bottom of the device, 10 slide up over the ends of the legs of the frame B, as shown in Fig. 2, so that the said fire-escape A shall be held steady and fast, and be prevented from swinging about.

The screw eyes or rings o consist of a ring 15 or eye, v, through which the legs of the frame B pass when the device is closed, as shown in Figs. 2 and 3, and of a shank, w, that passes through the ends of the lazy-tongs sections, connecting them together, said shank w being 20 screw-threaded, as shown at x, to hold firmly in the outside section of the said lazy-tongs, and through the slot b of the cross-bars A², said shank w being smooth, as shown at y, to work loosely in the inside lazy-tong section 25 and in the slot b. A beveled nut, z, is secured on the end of the shank w to hold said screw-eye o in place. For further security when closed, a hook or catch, p, may be secured on the lower cross-bar, A², and be caught in a corresponding staple, r, in the sill of the door or 30 window.

This device may be used as a fire-escape ladder, a painter's or mechanic's ladder, and as a door or window blind or shutter, or a

clothes-rack, and when hung as a blind or shutter may be kept from extending by passing the cord D' down through the screw-eyes a, and making it fast at the bottom, or by a bar passed down in front and made fast at top and bottom.

40

Having thus fully described our invention, we claim as new, and desire to secure by Letters Patent—

1. The combination, with the fire-escape A, provided with screw-eyes a and pulley i, of the 45 operating-rope E, substantially as herein shown and described, whereby said fire-escape is closed or extended, as set forth.

2. The combination, with the fire-escape A and rope E, of the swinging frame B, substantially as herein shown, and for the purpose described.

3. In a fire-escape, the combination, with the fire-escape A, frame B, and window or door frame C', of the elbow-lever D, substantially 55 as herein shown and described, whereby said fire-escape and frame are thrown open, as set forth.

4. In a fire-escape, the combination, with the fire-escape A, frame B, window or door frame C', and elbow-lever D, of the ropes E D', substantially as herein shown and described, whereby the fire-escape is operated.

JOHN ALFRED MOORE.
JAMES WILLIAM BROWN.
